VALVE CONTROL.

1,121,245.

Specification of Letters Patent. Patented Dec. 15, 1914.

Application filed February 19, 1913. Serial No. 749,483.

To all whom it may concern:

Be it known that I, ERNST HERKT, a citizen of the German Empire, residing at Kiel-Hassee, Germany, have invented certain new and useful Improvements in Valve Controls, of which the following is a specification.

This invention relates to those two-stroke cycle internal combustion engines in which a plurality of scavenging valves arranged in the cylinder cover, are controlled by a common controlling lever, through the interposition of a multiple-armed intermediate piece, and are so arranged that between them space is left free for the fuel valve. In such a valve-arrangement it is not always possible to have the controlling lever engaged exactly in the center of gravity of the intermediate piece, and when this is not accomplished, the unequal distribution of mass readily results in unbalance of the intermediate piece and through that, in an unequal control of the individual valves.

The invention aims to provide for the valves of the aforesaid type of internal combustion engines, a controlling means through which all of the valves will be uniformly controlled.

In the accompanying drawing, the subject-matter of the invention is shown by way of example, Figure 1 showing a vertical section through the working cylinder with the extreme right of the cylinder broken away, and Fig. 2 the top plan view belonging to Fig. 1.

In the cover A of a two-stroke cycle internal combustion engine, are arranged in a known manner, three scavenging valves C, which open toward the interior of the cylinder, and communicate through the medium of two flange-couplings a¹, with the main scavenging pipe, not shown. These scavenging valves are controlled from a controlling shaft D, with cam E, by a controlling lever F, F¹, acting upon said valves, in common, through the medium of a three armed intermediate piece H. The controlling lever is deflected and is carried by bearing blocks c¹, c², cast upon the housing of the scavenging valve C, lying between them. The part F of the controlling lever is forked and carries the controlling roller f².

The intermediate piece H, is straightly guided by a hollow cylindrical prolongation

H¹, in a likewise hollow cylindrical part J, rigidly connected with the cylinder cover. 55 The engagement of the arm F¹, of the controlling lever, with the intermediate piece is accomplished through the medium of a thrust-rod G, with spherical ends, and a pot-shaped shell L. The latter is introduced 60 into an opening in the prolongation H¹, and supports itself upon the annular projection L², through the medium of a flange i¹. The counter-bearing f³, provided on the controlling lever for the thrust-rod G, is exchangeable; a similar counter bearing forms the 65 bottom of the shell L. A helical spring K, surrounding the shell L, serves to sustain the three valve springs c³, belonging to the respective valves.

Introduced in an oblique direction in the space between the three scavenging valves C, is the fuel spraying valve M, which will likewise be controlled by a controlling cam disk, not shown.

The operation of the described controlling device will be recognized from the drawing without further discussion. By the straight-line guiding of the intermediate piece H, as compared with the operation of known 80 valve-controls of this type, the advantage is obtained of wholly preventing tipping of the intermediate piece, with the consequent unequal control of the three valves, which condition without this guide, could undoubtedly occur with the unequal lengths of the arms of the intermediate piece. Furthermore, should it be desired, as in known 85 valve-controls, to have the control-lever operate upon the intermediate piece from immediately above, there would be the circumstance of the tendency of the intermediate member to tip, even with the straight-line guide, which could induce one sided wear of the straight guide, or even a binding of the 90 part H¹ in the part J. This condition is effectively combated in the described controlling means, by having the point of engagement of the controlling lever F, F¹, at a very low point through the medium of the 95 thrust-rod G.

If in the course of time play enters in between the controlling lever and the intermediate member H, this can easily be eliminated by exchanging the counter-bearing f³, 105 for the thrust-rod G.

The spring K, sustains, on the one hand, the valve springs c³, in their operation inasmuch as it relieves them of the load of the intermediate piece; on the other hand, equally by this unloading, it prevents the uniformly acting valve-springs, in expanding against the intermediate piece, from exerting a tipping effect in consequence of the unequally distributed mass which, again, 10 could manifest itself in a one-sided wear of the straight guide or a binding of its parts.

I claim:

1. In a valve-controlling mechanism for two-stroke cycle internal combustion engines, the combination of a plurality of scavenging valves, a single controlling member and an intermediate piece serving in common for the several valves, a straight-line guide for said intermediate piece, and a bearing for the single controlling member upon the intermediate piece below the level of the latter.
2. In a valve-controlling mechanism for two-stroke cycle internal combustion engines, the combination of a plurality of scavenging valves, a single controlling member and an intermediate piece serving in common for the several valves, a straight-line guide for said intermediate piece, and a bearing for the single controlling member upon the intermediate piece below the level of the latter; said valves having individual springs, and said intermediate piece having its own spring relieving the valve-springs of the load of the intermediate piece.
3. In a valve-controlling mechanism for two-stroke cycle internal combustion engines the combination of a plurality of scavenging valves, with a single controlling member and an intermediate piece serving in common for the several valves, a straight-line guide for said intermediate piece, and a bearing for the single controlling member upon the intermediate piece below the level of the latter; said straight-line guide comprising a cylindrical prolongation on the intermediate piece and a coöperating cylindrical guide on the engine.
4. In a valve-controlling mechanism for two-stroke cycle internal combustion engines the combination of a plurality of scavenging valves, a single controlling member and an intermediate piece serving in common for the several valves, a straight-line guide for said intermediate piece, and a bearing for the single controlling member upon the intermediate piece below the level of the latter; said straight-line guide comprising a cylindrical prolongation on the intermediate piece and a coöperating cylindrical guide on the engine; said cylindrical prolongation being hollow and said bearing for the single controlling member being located within said prolongation.

5. In a valve-controlling mechanism for two-stroke cycle internal combustion engines, the combination of a plurality of scavenging valves, a single controlling member and an intermediate piece serving in common for the several valves, a straight-line guide for said intermediate piece, and a bearing for the single controlling member upon the intermediate piece below the level of the latter, and comprising a thrust-rod having jointed bearings against said single control member and said intermediate piece.

6. In a valve-controlling mechanism for two-stroke cycle internal combustion engines, the combination of a plurality of scavenging valves, a single controlling member and an intermediate piece serving in common for the several valves, a straight-line guide for said intermediate piece, and a bearing for the single controlling member upon the intermediate piece below the level of the latter, and comprising a shell projecting through said intermediate member and a thrust-rod extending between and having jointed bearings against the single-control member and the bottom of said shell.

7. In a valve-controlling mechanism for two-stroke cycle internal combustion engines, the combination of a plurality of scavenging valves, a single controlling member and an intermediate piece serving in common for the several valves, a straight-line guide for said intermediate piece, and a bearing for the single controlling member upon the intermediate piece below the level of the latter, and comprising a thrust-rod having jointed bearings against said single control member and said intermediate piece, and an exchangeable counter bearing for said rod, on the single controlling member.

8. In an internal combustion engine having a plurality of valves each provided with its own independent spring, in combination a multiple-arm intermediate piece serving in common for all the valves to actuate them simultaneously, a spring for said intermediate piece, relieving the valve-springs of the load thereof, an elongated hollow cylindrical prolongation on said intermediate piece, a hollow cylindrical guide on the engine in which said prolongation works, a thrust-rod bearing upon the intermediate piece below the plane of the arms thereof, and a single controlling lever bearing upon said thrust-rod.

9. In an internal combustion engine having a plurality of valves each provided with its own independent spring, in combination a multiple-arm intermediate piece serving in common for all the valves to actuate them simultaneously, a spring for said intermediate piece, relieving the valve-springs of the load thereof, an elongated hollow cylindrical prolongation on said intermediate piece, a

hollow cylindrical guide on the engine in which said prolongation works, a thrust-rod bearing upon the intermediate piece below the plane of arms thereof, and a single 5 controlling lever bearing upon said thrust-rod, there being a pot-shaped shell extended through and into the prolongation of the intermediate member and providing the

bearing for the thrust-rod and the guide for the spring on said intervening member.

In testimony whereof I have affixed my signature in presence of two witnesses.

ERNST HERKT.
